DUPLEX ENVELOPE

William Allen Jenrich, Chicago, Ill.

Application December 26, 1930
Serial No. 504,779

3 Claims. (Cl. 229—72)

This invention relates to improvements in envelopes and more particularly to the envelopes of the duplex type. One object is to provide an envelope of this class that is formed from a single piece of stock and that is consequently inexpensive in its manufacture. A further object is to provide a duplex envelope comprising a large and a small compartment, the latter being adapted to be sealed when in use. A further object is to provide an envelope that requires but few mechanical operations in its manufacture, that is efficient in use, and attractive in appearance.

With the foregoing and other objects in view the invention consists in the combination and arrangement of parts to be hereinafter fully described, pointed out in the claims and illustrated in the accompanying drawings which form a part of this application for patent and 20 in which—

Fig. 1 is a plan view of the envelope cut, mucilaged and ready to be folded for use.

Fig. 2 is a view of the envelope partly folded, the smaller compartment being ready for use.

Fig. 3 is a view of the envelope completely folded and ready to mail.

Fig. 4 is a vertical sectional view taken on the line 4—4 of Fig. 2.

Fig. 5 is a similar view taken on the line 5—5 20 of Fig. 3, or of Fig. 10.

Fig. 6 is a cross-sectional view taken on the line 6—6 of Fig. 3, or of Fig. 10.

Fig. 7 is a view similar to Fig. 1 but of a slightly modified form of envelope.

Fig. 8 is a similar view of the envelope shown in Fig. 7, partly folded.

Fig. 9 is a view of the envelope shown in Fig. 8, with one flap partly broken away, after being further folded.

Fig. 10 is a view of the modified form of envelope complete, folded and ready to be mailed.

Like reference characters denote corresponding parts throughout the several views.

The envelope is formed from a single blank 45 of material which includes the main body portion or larger compartment 1 which is slotted to form the flap 2 and scored along the edge 3 as denoted by dotted lines. Integral with the larger compartment 1 is the strip 4 which when 50 folded along the lines 5 against the larger compartment or body 1 forms the smaller or first class mail compartment, said strip being formed with the flap 6 having the gummed portion 7, said strip proper being formed with the gummed 55 portions 8, 9.

When the strip 4 is folded against the body 1 the flap 6 is inserted through the slot formed by cutting the body flap 2 and thereafter said flap 2 is permanently secured to the reverse side of the flap 4, the gummed portions 8, 9 of said flap being then sealed to the said body 1 and the flap 6 is now in position to be sealed against the body 1 after the first class mail has been deposited in the receptacle provided therefor and formed at 24 between the strip 4 and body portion 1. After said flap 6 is sealed shut it will be noted that the compartment 24 is open at its lower end as clearly shown in Fig. 5.

The body portion 1 is formed in Figs. 1 to 6 inclusive with the integral oppositely disposed flaps 10, 14, and with the lateral flap 19, the flap 10 being adapted to be folded along the dotted line 11 against the body 1 and against the said small compartment 24, said flap 10 being formed with the gummed lateral tongue 12 adapted to be folded along the line 13 against the front face of the body 1, or upon the side thereof opposite to that against which said flap 10 is folded.

The flap 14 is now folded along the line 15 against the strip 4 and flap 10, said flap 14 having a gummed edge 16 which is permanently sealed to said flap 10, and a minor gummed flap 17 which is then folded along the line 18 against the face side of the envelope body 1, slightly overlapping the lower end of the tongue 12, said minor flap 17 being now sealed in position, the compartments 24, 23 are now completed, the latter compartment being formed by the body 1 and flaps 10, 14.

In Figs. 7 to 10 inclusive the body 1 is formed with the tongue 13' and the flap 10 is provided along one edge with the gummed portion 12' and in forming this envelope the strip 4 and tongue 13' are folded along the line 5 at the same time. The flap 10 is now folded down along the line 11 upon the body portion 1 and tongue 13' and sealed to the latter along the gummed portion 12'. The flap 14 is now folded along the line 15 to rest against the strip 4 and flap 10 and sealed thereupon by means of its gummed portion 16. The gummed minor flap 17 is now folded upon the line 18 against the face of the body 1 and sealed thereto as shown in Fig. 10. If preferred the minor flap 17 may be gummed upon its reverse side to that shown in Figs. 7 and 8 and then folded along the line 18 against the flap 14 and then folded, together with flap 14, against the flap 10 in substantially the same manner as the 110

tongue 13' in Figs. 8 and 9, said gummed portions 17 and 16 then being sealed to said flap to complete the compartments 23 and 24. In this event the front face of the completed envelope will not disclose any flaps except the flap 6.

Referring now to all figures, the body 1 is formed with a cut-out or window portion 21 which may be covered by a strip of glassine paper 22 in a well known manner to expose the address upon a printed form letter; or like matter, which may be inserted in the smaller compartment. This window feature may, however, be omitted and the address placed directly upon the envelope. When the envelope is occupied the ungummed flap 19 is folded along the line 20 and preferably tucked inside the envelope between the flaps 14, 10 and the body 1. Withdrawal manually of this flap 19 permits ready access to the contents of the large compartment.

The printed lines 25 shown in Fig. 3 denote the presence of the smaller compartment 24. Third class and first class postage are denoted, respectively, at 26 and 27.

What is claimed is:—

1. A duplex envelope formed of a single piece of material including a body portion, said body portion being slotted transversely, oppositely disposed flaps formed upon said body portion, an ungummed flap formed laterally of said body portion, a tongue formed laterally of said body portion diagonally opposite to said ungummed flap, a narrow strip formed laterally of said body portion upon the side thereof common to said tongue, and a flap for said strip, said strip being adapted to be folded back upon said body portion and said flap for disposal in said body slot, said oppositely disposed flaps being adapted to be folded inwardly upon said strip and body portion and overlapping each other, said tongue being adapted to be folded against said body portion and said ungummed flap being then tucked in between said oppositely disposed flaps and said body portion.

2. A duplex envelope formed of a single piece of material including a body portion, said body portion being slotted transversely, oppositely disposed flaps formed upon said body portion, a minor flap formed laterally of one of said last named flaps, an ungummed flap formed laterally of said body portion, a tongue formed laterally of said body portion upon the side opposite to said ungummed flap, a strip formed laterally of said body portion upon the side common to said tongue, said strip being adapted to be folded back upon said body portion, and a flap for said strip, said flap being adapted for disposal in said body slot, said oppositely disposed flaps being adapted to be folded inwardly upon said strip and body portion and overlapping each other, said tongue being adapted to be folded upon one side of said body portion, said minor flap being adapted to be folded upon the same side of said body portion, said ungummed flap being then tucked in between said oppositely disposed flaps and said body portion.

3. A duplex envelope formed of a single piece of material including a body portion, said body portion being slotted transversely, oppositely disposed flaps formed upon said body portion, a tongue formed laterally of one of said flaps, a minor flap formed laterally of the other flap, an ungummed flap formed upon said body portion, a strip formed laterally of said body portion, and a flap for said strip, said strip being adapted to be folded upon said body portion and said flap for disposal in said body slot, said oppositely disposed flaps being adapted to be folded inwardly upon said strip and body portion and overlapping each other, said flap tongue and minor flap being adapted to be folded against the face of said body portion, said ungummed flap being then tucked in between said oppositely disposed flaps and said body portion.
